ANTENNA MOUNTING

Alexander Rauch, Eatontown, N. J., assignor to
the United States of America as represented by
the Secretary of War

Application June 5, 1946, Serial No. 674,409

3 Claims. (Cl. 250—33)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention relates to antennas and particularly to biconical antenna assembly mountings.

Antenna assemblies designed for field use are subjected to extremely rough usage. It is therefore an object of the invention to provide an antenna mounting that shall be rugged, durable and compact.

It is another object of the invention to provide an antenna mounting assembly that shall be waterproof.

It is a further object of the invention to provide an antenna assembly that shall include a minimum of parts, in order that repairs may quickly and easily be made.

It is a still further object of the invention to provide an antenna that may quickly be adapted to operate on a large number of frequency bands.

These objects, together with other objects and advantages of the invention which will be apparent to one skilled in the art, are achieved in one embodiment of the invention by means of an axially symmetrical assembly including a metallic head having at least three upwardly and outwardly extending radiator sockets formed therein and a metallic, annular base plate having at least three downwardly and outwardly extending radiator sockets, said head sockets and said plate sockets forming the same angle with the axis of the assembly. The antenna is fed by means of a coaxial cable, the outer conductor of said cable being connected to the base plate and the inner conductor being connected to the head. Annular dielectric spacers and rubber washers are provided between all mating surfaces in order to both insulate the assembly electrically and to shock mount and waterproof the assembly. The inner conductor of the coaxial cable extends through the assembly to engage the head electrically and mechanically, the inner conductor thus serving both to electrically feed the head and to draw the assembly together rigidly.

For a better understanding of the invention reference is made to the following specification of one embodiment of the invention, the said specification to be read in connection with the accompanying drawings, in which

Figure 1 is a perspective view of a device embodying the invention;

Figure 2 is a cross sectional view in elevation of the device shown in Figure 1.

2

Figure 3 is an exploded view of one feature of the invention.

Figure 4 is a view of another feature of the invention.

5 Referring to the drawings, there is shown a biconical antenna comprising an upper cone consisting of three fed radiators 10 and a lower cone consisting of three grounded radiators 12. The three fed radiators 10 are respectively threadably mounted 120° apart in three bored radiator sockets 6 formed in a downwardly tapering, metallic head 14, and extend outwardly and upwardly therefrom, at a uniform angle to the vertical, to form, electrically, a radiating cone. The sockets 6 are provided with drain holes 8 to permit drainage of moisture from said sockets.

The three grounded radiators 12 are respectively threadably mounted in three radiator receptacles 16. The receptacles 16 are disposed 120° apart about the tapered undersurface 18 of an annular, axially apertured base plate 20, and extend outwardly and downwardly at the same angle to the vertical that exists between the fed radiators 10 and the vertical.

20 15 25 The base plate 20, formed of an electrically conductive material, is provided with a flat upper surface 22 and with a pyramid-like lower surface consisting of a flat downwardly extending surface 18 and an upwardly tapering surface 24. 30 The surface 24 is terminated a short distance before the periphery of the centrally located orifice 26 is reached, the undersurface of plate 20 immediately adjacent said orifice being parallel to the upper surface 22 of the plate.

35 35 The base plate 20, bearing radiator receptacles 16 and grounded radiators 12 mounted therein, is electrically and mechanically connected to an antenna supporting mast 28 by means of a metallic coupling unit 30 and three metallic, U-channel legs 32.

40 45 The coupling unit 30 comprises a cylindrical resilient coupler 34 having a longitudinal slot along the lower end thereof. Positioned about the longitudinally cut portion of said coupler 34 is a ring clamp 36 having the outwardly extending arms 38 thereof apertured to receive a locking wing nut 40.

45 50 The three legs 32 are connected between base plate 20 and the upper portion of the coupler 34. The upper ends of legs 32 are fixed to base plate 20 by screws 42 and are riveted to coupler 34.

55 55 The antenna mast 28 is formed of an electrically conductive material and is grounded by being sunk in the earth or by being electrically connected to a grounded apparatus.

The head 14, bearing radiator elements 10, is positioned above base plate 20 and is electrically insulated therefrom by means of dielectric spacers 44 and 46.

Dielectric spacer 44 is provided with an upper outside diameter complementary to orifice 26 formed in plate 20 and is provided with a larger lower outside diameter to form a shoulder 48 to engage the undersurface of plate 20 about the periphery of the orifice. The portion of the dielectric spacer 44 that is defined by the upper outside diameter is slightly greater in length than the thickness of the plate 20 immediately about the periphery of the orifice 26.

The spacer 44 is provided with a square axial bore complementary to a square lock stop 50 formed on the inner conductor 52 of a coaxial cable connector 54. The spacer 44 is also provided with an annular axial recess formed in its lower surface complementary to the outside diameter of said coaxial cable connector.

The dielectric spacer 46 is generally cylindrical and is provided with an axial bore complementary to inner conductor 52 of coaxial cable connector 54. An annular recess is formed in the lower surface of spacer 46 complementary to the diameter of the upper portion of spacer 44. The spacer 46 is further provided with an annular axial recess formed in its upper surface, the said recess being slightly larger in diameter than the lower surface of head 14.

The coaxial cable connector 54 comprises an outer conductor 56 and an inner conductor 52 coaxial therewith, the said conductors being electrically insulated from each other by means of a dielectric cylinder 58 having an outwardly extending flange about its upper end. The cylinder 58 is pressed into the space between the inner and outer conductors 52, 56 and serves both to electrically insulate the conductors from each other and also to rigidly position the conductors with respect to each other.

The outer conductor 56 is externally threaded to receive an electrically conducting ring 60. A flexible metal band 62 is connected between ring 60 and grounded base plate 20.

The portion of inner conductor 52 lying within outer conductor 56 is formed to provide a standard female terminal to mate with the standard male terminal customarily formed on the end of coaxial cable. The portion of inner conductor 52 immediately beyond the upper limit of the outer conductor 56 is substantially square in cross section. The remainder of inner conductor 52 is circular in cross section and is externally threaded to engage a threaded axial bore formed upwardly in head 14 from the lower surface thereof.

The inner conductor 52 serves both to electrically feed upper radiators 10 and to hold head 14 firmly in spaced relationship with plate 20.

Thus, to assemble the assembly mounting, spacer 44 is first inserted upwardly into orifice 26. The recess formed in the lower surface of spacer 46 is then fitted about that portion of spacer 44 extending above upper surface 22 of plate 20. The inner conductor 52 of coaxial cable connector 54 is then passed upwardly through the axial bores of spacers 44, 46, the square portion 50 of inner conductor 52 locking in the square axial bore formed in spacer 44. The head 14 is then threaded on the portion of the inner conductor 52 extending above the spacer 46 and the entire assembly is drawn tight.

In order to waterproof the assembly, and also

in order to shock mount the dielectric spacers 44, 46, rubber washers are provided between each mating surface. A rubber washer 64, having an outside diameter equal to the diameter of the recess formed in the lower surface of spacer 44, and having a square axial perforation complementary to the square portion 50 formed along inner conductor 52 is seated in the said recess.

A rubber washer 66 is provided adapted to fit snugly against shoulder 48 of spacer 44. A rubber washer 68 is positioned about that portion of spacer 44 extending upwardly beyond surface 22, the outer diameter of said washer being greater than the outer diameter of spacer 46. A rubber washer 70 is positioned in the recess formed in the upper surface of spacer 46. A metal disc 72 having the same dimensions as rubber washer 70 is positioned immediately above the said washer in said recess, the purpose of said disc being to prevent shearing of washer 70 by head 14 as the assembly is drawn tight.

The antenna having thus been assembled, electrical connection is made to coaxial cable connector 52. The coupler 34 is then positioned about the upper portion of the antenna mast 28 and is tightened thereon by means of clamp 36 and wing lock nut 40. The antenna assembly is then in readiness to be raised and used.

As is well known, the optimum frequency at which a biconical antenna will operate is determined both by the angle of opening between the cones and by the electrical length and width of the cones. The biconical antenna disclosed herein is axially symmetrical and is provided with a fixed angle between cones, which angle, of course, may be varied throughout a series of antennas. The device disclosed herein, however, is adapted to receive radiating elements of varying lengths, since all of the radiating elements 10 and 12 are threadably connected to the assembly. Thus, if it is desired to operate on a plurality of frequencies at which radiation shall be transmitted or received, radiators of optimum length for each frequency may be chosen.

There has thus been disclosed a rigid, easily assembled, waterproof antenna that is designed to operate over a wide range of frequencies. It will be obvious that many modifications and changes may be made in the specific embodiment disclosed herein. For example, the head 14 may be provided with a single, axially extending, replaceable radiator to replace the three upwardly and outwardly extending radiators 10. It is therefore intended that the full scope of the invention be defined by the attached claims.

What is claimed is:

- An axially symmetrical biconical assembly comprising a metallic head having at least three upwardly and outwardly extending sockets formed therein, a metallic, annular base plate bearing at least three downwardly and outwardly extending radiator sockets, said head sockets and said plate sockets forming the same angle with the axis of said assembly; a first, annular, dielectric spacer positioned between said head and said plate, a rubber washer positioned between said base plate and said first spacer, a second rubber washer and a metallic washer positioned between said spacer and said head; a resilient, metallic coupler, metallic legs to connect said coupler and said plate; a coaxial cable connector comprising an outer conductor and an elongated, externally threaded, inner conductor coaxial therewith, means to connect electrically said outer conductor to said base plate, and means to insulate said inner conduct-

tor from said base plate, said inner conductor extending upwardly through said washers, plate and spacers to engage mechanically and electrically said head.

2. An axially symmetrical biconical assembly comprising a metallic head having at least three upwardly and outwardly extending sockets formed therein, a metallic, annular base plate bearing at least three downwardly and outwardly extending radiator sockets, said head sockets and said plate sockets forming the same angle with the axis of said assembly, a first, annular, dielectric spacer positioned between said base plate and said first spacer, a second rubber washer and a metallic washer positioned between said spacer and said head; a resilient, metallic coupler, metallic legs to connect said coupler and said plate; a coaxial cable connector comprising an outer conductor and an elongated, externally threaded, inner conductor coaxial therewith; a flexible, metallic band to connect electrically said outer conductor to said plate; a second annular, dielectric spacer positioned between said outer conductor and said base plate, a portion of said second spacer extending axially through said plate, a rubber washer positioned between said spacer and said plate, a rubber washer positioned between said

second dielectric spacer and said outer conductor, said inner conductor extending upwardly through said washers, plate and spacers to engage mechanically and electrically said head.

5 3. The device according to claim 2, which includes means to connect said antenna assembly to an antenna mast, said means comprising a resilient metallic coupler to engage said antenna mast and metallic legs to connect said coupler to said plate.
